UNITED STATES PATENT OFFICE.

FREDERICK ERNEST LOW, OF LONDON, ENGLAND, ASSIGNOR TO BEWLAY AND COMPANY LIMITED, OF LONDON, ENGLAND.

TOBACCO PIPE AND CIGAR AND CIGARETTE HOLDER.

Application filed November 29, 1921. Serial No. 518,599.

To all whom it may concern:

Be it known that I, FREDERICK ERNEST Low, a subject of the King of Great Britain, residing in London, England, have invented 5 certain new and useful Improvements in and Relating to Tobacco Pipes and Cigar and Cigarette Holders, of which the following is a specification.

This invention relates to tobacco pipes, 10 cigar and cigarette holders, and refers to pipes or holders in which for cooling the smoke and keeping the bore of the stem and mouthpiece clear there is provided a metal body, connected by a slot to the end of the 15 push portion of the mouthpiece, which body is twisted into a more or less spiral form.

Heretofore the attachment of the spirals to the push portion of the mouthpiece has been secured by slotting the material of the 20 push portion, the flat intermediate portion of the cooling and clearing device engaging in this slot. In practice, it is found that the engagement in and disengagement of this flat portion from the slot injures the material so that firm connection of the parts is 25 no longer possible.

Slotting the material to permit engagement of the flat portion of the clearing device has a tendency to weaken the material 30 which may break away at this point so that the utility of the cooling and clearing device is impaired or its use no longer possible.

The present invention has for its object certain improvements designed to overcome 35 the aforesaid disadvantages.

According to this invention the bore of the mouthpiece at the push portion, or end of the mouthpiece which is insertible in the stem, is increased in diameter for a distance 40 from the extreme end inwardly to form a recess in which is secured in any convenient manner a metal or other bushing or tube of wear resisting material. The free end of the push portion is slotted at diametrically opposite points and slots are formed 45 in said tube or bushing coinciding with those in the push portion.

It will thus be seen that when in position the flat intermediate portion of the cooling 50 and clearing device engages in the slots in the metal tube so that the effort when the mouthpiece is rotated, instead of falling upon the softer material, vulcanite for example, falls upon the bushing whereby 55 damage or wear to the stem engaging end

of the push portion is avoided, and at the same time the means of connection is such as to permit the ready removal and replacement of the clearing and cooling device without damage to the mouthpiece. 60

In order that the invention may be the better understood drawings are appended in which—

Fig. 1 is a side view partly in section of a pipe embodying the present invention. 65

Fig. 2 is a fragmental longitudinal sectional view on a larger scale than Fig. 1, of the mouthpiece removed from the pipe.

Fig. 3 is a fragmental sectional side view of the mouthpiece on the same scale as Fig. 2. 70

Fig. 4 is an end view of same.

Fig. 5 is a fragmental longitudinal sectional view, on a larger scale than the former views, of the stem and mouthpiece 75 and the cooling and clearing device.

Fig. 6 is a detail view, on same scale as Fig. 5, of the cooling and clearing device.

Fig. 7 is a fragmental detail sectional view, on same scale as Fig. 5, of the mouthpiece and the push portion of the mouthpiece. 80

Fig. 8 is a detail sectional view, on same scale as Fig. 5, of the bushing or lining for the mouthpiece, and 85

Fig. 9 is a fragmental sectional view, on same scale as Fig. 5, of the end of the stem.

Similar reference characters denote similar parts throughout the several views.

Referring to the accompanying drawings, 90 *a* indicates the pipe bowl, *a'* the stem, *b* indicates the mouthpiece and *b'* the push portion. The device for cooling and clearing the bores of the stem and mouthpiece is a length or strip *c* of material, aluminum for example, having a flat intermediate portion *c'* extended at its sides and forming laterally extending lugs *c*² shown in Figs. 5 and 6, the strip at each end of the flat portion being twisted into spiral or helical form, 95 in practice the cooling and clearing device extending when in operative position through the bore of the stem from near the junction of this bore with the interior of the bowl, through the bore of the bushing *d* in the push portion and through the bore of the mouthpiece to a point near the bit or outer end thereof. As shown in Figs. 2, 5 and 7, the bore of the end of the push portion *b'* is enlarged to provide a recess, and 100 105 110

secured therein either by friction or other suitable manner is a bushing or liner d , preferably of such length as to project somewhat beyond the free end of the push portion for reception in the bore of the stem, so that in placing the device c in operative position in the mouthpiece, or in operating the device, it engages said bushing and not the softer material of the push portion b' , thus avoiding injury thereof.

The bushing d is slotted at diametrically opposite points d' , corresponding slots b^2 being formed in the push portion b' , and when the device c is in operative position in the stem and mouthpiece the lugs c^2 engage in the slots d' and b^2 .

Obviously the invention may be applied to cigar and cigarette holders.

Claims:

- 20 1. In a device of the character described, the combination of, a stem having a recess at one end and a bore communicating with the recess, a mouthpiece having a bore and having a push portion insertible in the recess of the stem and having a recess in the push portion provided with opposed longitudinally extending slots, a bored bushing in the recess of the mouthpiece communicating with the bore of the mouthpiece and with the bore of the stem when the push portion is inserted in the stem and having longitudinally extending slots registering with the slots of the push portion, and a

cooling and clearing device having helical ends and a flat intermediate portion forming laterally extending lugs; the respective helical ends, when the cooling and clearing device is in operative position, being located in the bore of the stem and in the bore of the mouthpiece and the flat intermediate portion being located in the bore of the bushing and said laterally extending lugs engaging in the registering slots of the bushing and mouthpiece and extending into the recess of the stem.

40 2. In a device of the character described, the combination of, a mouthpiece having a bore and having a push portion communicating with said bore and provided with a recess having opposed longitudinally extending slots, and a bored bushing in the recess of the push portion communicating with the bore of the mouthpiece and having opposed longitudinally extending slots registering with the slots of the push portion.

45 3. In a device of the character described, a cooling and clearing device comprising helical end portions and a flat intermediate portion extended at its sides for providing laterally extending lugs.

50 In witness whereof I have hereunto set my hand in the presence of two witnesses.

FREDERICK ERNEST LOW.
